LA VERNE O. ELLINGSON
WHISTLING CAP FOR GAS APPLIANCES

2,549,300

Filed Oct. 11, 1946

UNITED STATES PATENT OFFICE

2,549,300

WHISTLING CAP FOR GAS APPLIANCES

La Verne O. Ellingson, Monrovia, Calif., assignor
to Lowell and Grayson Manufacturing Company, Monrovia, Calif., a corporation of California

Application October 11, 1946, Serial No. 702,793

4 Claims. (Cl. 137—102)

1

This invention relates to a new and improved whistle cap for gas appliances for the purpose of purging the line of air at the time of installation of the appliance, the audible signal given by the cap when loosened to allow air flow through it being used to remind the plumber or other workman to be sure to close the cap gas-tight before leaving the job, the invention being herein illustrated as applied to a thermostatic gas valve designed and adapted to be used in connection with storage type water heaters.

The principal object of my invention is to provide a device of the kind mentioned in which an easily vibratable musical reed is mounted inside a closure cap loosely covering an elongated slot provided in the threaded shank portion of the cap, whereby when the cap is loosened the escaping air, and, later, gas, will vibrate the reed so as to give a whistling sound to serve as a reminder to the installer not to leave the cap loose any longer than necessary after the gas has arrived at the pilot light.

The invention is illustrated in the accompanying drawing, in which

Figs. 1 and 2 are a side view and inner end view, respectively, of a whistle cap made in accordance with my invention;

Fig. 3 is a view partly in section on the line 3—3 of Fig. 4, and partly in side elevation of a thermostatic gas valve equipped with the whistle cap, the valve being shown applied to the tank of a storage type water heater;

Fig. 4 is an end view of Fig. 3, showing the whistle cap in end elevation, and

Fig. 5 is a cross-section on line 5—5 of Fig. 3, with the valve shown in open position.

The same reference numerals are applied to corresponding parts throughout these views.

Referring to the drawing, in which a thermostatic gas cock similar to that forming the subject matter of John H. Grayson application, Serial No. 629,592, filed November 19, 1945, now Patent No. 2,524,788, dated October 10, 1950, is disclosed, the reference numeral 6 designates a cast hollow valve body, the neck 7 of which is threaded into an adaptor 8 suitably fixed in the wall 9 of the tank of a gas burning water heater, 10 and 11 designating the tube and rod elements of the thermostat projecting into the tank to cause the operation of the valve in response to changes in temperature of the water. Without going into the details, the valve 12 which is normally closed by means of a spring 13 will when the thermostat is cooled off by reason of a drop in temperature of the water open the valve by 55 whereupon the valve 12 snaps to closed position

2

means of the push rod 14, the valve being shown in the opened position in Fig. 3, in spaced relation to the seat 15 provided on the outer end of the tapered plug 16. The plug 16 fits in a tapered bore 17 in the body 6 and is rotatable through 90° by means of a lever 18 working in a slot 18' provided in the wall of the body 6. The body 6 has a hollow neck 19 cast integral therewith into which the gas supply pipe 20 is threaded for delivery of gas through a radial port 21 communicating with the bore 17. An arcuate passage 22 in the periphery of the plug 16 extends through 90°, as shown in Fig. 5, and in the "on" position of the plug establishes communication between the port 21 and another radial port 23 in the body, the latter port communicating with a longitudinal passage 24 that has communication with a chamber 25 in the end of the body communicating with the large end of the bore 17 and closed by a plug 26. This plug has a central recess 27 therein in which the large end of the conical spring 13, mentioned previously, is seated. When the valve 12 is open and plug 16 is in the "on" position, it is, therefore, clear that gas is delivered to the axial bore 28 in the plug 16 and is conducted through a radial outlet port 29 and through an outlet pipe 30 to the burner (not shown) for heating the water in the tank 9 in the usual way. A sleeve valve 31 which is inserted with a close working fit in an enlargement 32 of one leg of the L-shaped passage 33 provided in the body 6 has a radial port 34 communicating with the other leg of said passage, and one end of the sleeve 31 is closed, as indicated at 35, and has a screw driver slot provided therein to permit turning the valve 31 for permanently restricting the flow of gas to the burner accordingly as the gas pressure in a given locality may require. A plug 36 closes the hole 37 in the body 6 through which access may be had to the slot in the end of the valve 31 and serves to seal the body against gas leakage at this point.

In operation, the plug 16 is turned by means of the lever 18 to "on" position when the burner of the gas appliance, such as a water heater, is to be lighted. After that, assuming the sleeve valve 31 is provided, this valve is adjusted according to the gas pressure so that the burner operates efficiently and with the right sized flame. The valve 12 remains open until the water in the tank reaches a predetermined temperature for which the thermostat 10—11 has been adjusted, as described in the Grayson application, 50 whereupon the valve 12 snaps to closed position

and remains closed until there is a sufficient drop in temperature of the water in the tank to cause the thermostat to open the valve. A pilot light (not shown) is supplied with gas from the supply pipe 20 through the usual bypass in the usual way and is disposed adjacent the main burner to ignite it.

In accordance with the present invention an elongated slot 38 is provided in the threaded shank portion 39 of the cap 26 and an easily vibratable musical reed 40 is soldered or otherwise suitably secured at one end 41 to the inside of the shank portion 39 so that the reed loosely covers the greater portion of the slot, as clearly appears in Figs. 1 and 2, whereby when the cap 26 is loosened by means of a wrench applied to the square embossed portion 42 at the time of installation of the water heater or other appliance in connection with which the valve of which the cap 26 forms a part is used, the escaping air, and later, gas, will vibrate the reed 40 so as to give a whistling sound and serve as a reminder to the plumber or other workman making the installation of the appliance to be sure to close the cap 26 gas-tight before leaving the job. In fact, the whistle will be sufficiently noticeable so that the average workman is not apt to leave the cap loosened any longer than necessary after the gas has arrived at the pilot light and the pilot light can be lighted and the main burner lighted thereby. With my invention, the gas pipes may be purged of air quickly and easily and without even a remote likelihood of a careless workman leaving the job with gas leaking in an amount sufficient to constitute a real hazard to the household where the installation is made. A gasket 43 is compressed between the rim 44 of the cap 26 and the valve body 6 when the cap is tightened, whereby to prevent gas leakage.

It is believed the foregoing description conveys a good understanding of the objects and advantages of my invention. The appended claims have been drawn to cover all legitimate modifications and adaptations.

I claim:

1. In a gas valve, comprising a body having a threaded opening and containing a valve, thermostatic means for opening the valve, spring means for closing the valve, and a closure cap having a shank portion threaded in said opening to close the same normally gas-tight, said cap providing also an abutment for said spring means, the improvement which consists in the provision of a slot in the shank portion of said cap arranged to be uncovered by loosening the cap for escape of air in purging the gas line to the valve of air in the installation of the valve, and a slender vibratable sound producing reed mounted on the inside of said shank portion loosely covering at least the major portion of said slot and adapted to be vibrated and sounded by flow of air and gas through the slot.

2. In a gas valve, comprising a body having a threaded opening and containing a valve, and a closure cap having a shank portion threaded in

said opening to close the same normally gas-tight, the improvement which consists in the provision of a slot in the shank portion of said cap arranged to be uncovered by loosening the cap for escape of air in purging the gas line to the valve of air in the installation of the valve, and a slender vibratable sound producing reed mounted on the inside of said shank portion loosely covering at least the major portion of said slot and adapted to be vibrated and sounded by flow of air and gas through the slot.

3. In a gas valve, comprising a body having a threaded opening and containing a valve, and a closure cap having a shank portion threaded in said opening to close the same normally gas-tight, the improvement which consists in the provision of a slot in the shank portion of said cap arranged to be uncovered by loosening the cap for escape of air in purging the gas line to the valve of air in the installation of the valve, a slender vibratable sound producing reed mounted on the inside of said shank portion loosely covering at least the major portion of said slot and adapted to be vibrated and sounded by flow of air and gas through the slot, said cap having a radially projecting rim portion in outwardly spaced relation to said slot, and a compressible gasket surrounding said shank between said rim and said slot.

4. In a gas valve, comprising a body having a threaded opening and containing a valve, thermostatic means for opening the valve, spring means for closing the valve, and a closure cap having a shank portion threaded in said opening to close the same normally gas-tight, said cap providing also an abutment for said spring means, the improvement which consists in the provision of a slot in the shank portion of said cap arranged to be uncovered by loosening the cap for escape of air in purging the gas line to the valve of air in the installation of the valve, a slender vibratable sound producing reed mounted on the inside of said shank portion loosely covering at least the major portion of said slot and adapted to be vibrated and sounded by flow of air and gas through the slot, said cap having a radially projecting rim portion in outwardly spaced relation to said slot, and a compressible gasket surrounding said shank between said rim and said slot.
